(57) **CLAIM**

The ornamental design for a light fixture, as shown and described.

DESCRIPTION

FIG. 1 is a front perspective view of a light fixture showing our new design;

FIG. 2 is a front view thereof;

FIG. 3 is a top perspective view thereof; and,

FIG. 4 is a left side perspective view thereof.

The broken line showing of various regions and the unshaded areas therein form no part of the claimed design.

1 Claim, 2 Drawing Sheets

FIG. 1

FIG. 2

FIG. 3

FIG. 4
